William Stellner

By *Samuel J. Quinley*
Attorney.

UNITED STATES PATENT OFFICE.

WILLIAM STELLNER, OF COLLINGWOOD, MELBOURNE, VICTORIA, AUSTRALIA.

PROPELLER.

Application filed January 4, 1926, Serial No. 79,152, and in Australia February 26, 1925.

This invention relates to propellers and more particularly to screw type propellers for marine work.

The object of the invention is to provide an improved propeller of the above type which is extremely simple in design and construction, highly efficient in operation, and reduces vibration and power losses to a minimum.

10 The invention resides primarily in a screw propeller having a plurality of inclined blades, each of which constitutes a sector of a circle defined by the outer edges or tips of the blades, the combined frontal 15 area of said blades being substantially equal to a complete circular area bounded on the outside by the tips of the propeller blades and on the inside by the peripheral surface of the propeller hub. In other words the 20 blades of the propeller form sectors of a complete circle, so that if placed together in a flat state with their side edges abutting the blades would form a complete disc as hereinafter described.

25 Referring to the drawings which form part of this specification:—

Figure 1 is a diagram illustrating by dot and dash lines the subdivision of a complete circle or disc to form a six bladed propeller 30 in accordance with the invention.

Figure 2 is a front view on a larger scale of a six bladed propeller in accordance with the invention.

Figure 3 is a fragmentary section taken 35 approximately on the line A—A of Figure 2.

Figure 4 is a plan of Figure 2.

Figure 5 is a fragmentary view of a single propeller blade according to a preferred construction.

40 Figure 6 is a section on line B—B of Figure 5.

Figure 7 is a section on line C—C of Figure 5.

Figure 8 is a section on line D—D of 45 Figure 5.

Figure 9 is a plan of a modification.

In accordance with the invention, each 50 blade of the propeller is of somewhat triangular shape having an outer peripheral edge 2, preferably of arcuate form, a leading side edge 3 and a trailing side edge 4, these two side edges converging radially towards the axis of the propeller so as to form a relatively narrow root portion 6, which joins the propeller hub 7, and is 55 preferably of considerably less width than

the width or length of said hub as shown. The corners of the blades are preferably rounded as at 8.

As seen in Figures 3, 4 and 9, the blades 60 are inclined at a suitable angle to the axis of the propeller shaft 9, thereby forming openings or passages, indicated at 10, between the adjacent blades as clearly seen in Figure 3. These openings or passages 65 gradually decrease in area from the outer to the inner ends of the blades and are thus substantially V shaped when viewed from the front of the propeller as in Figure 2. It will here be seen that the openings 10 70 are relatively narrow and of considerably less width than the width of the blades.

The width of the passages or spaces 10 between the blades depends solely upon the 75 inclination or pitch of said blades, the width and formation of which is such that they form sectors of a complete circle or disc as indicated in Figure 1 where the radial broken lines (a) indicate the side edges of the propeller blades and the dotted circle 80 (b) indicates the periphery of the propeller hub. The circular area between this dotted hub circle (b) and the outer circle (c) which coincides with the tips of the blades, is substantially equal to the combined frontal area 85 of all the blades of the propeller, or, in other words, if all the blades were placed flat or in the same circumferential plane at right angles to the propeller axis and with their side edges abutting, they would 90 form a complete disc. By this characteristic constructional feature, a maximum effective blade area is provided within a minimum space and it has been proved by practical tests that a propeller constructed in 95 the manner indicated provides a marked increase in efficiency, both as regards greater thrust and reduced vibration, as compared with existing propellers.

The front face 11 of each propeller blade 100 in accordance with the invention is preferably flat as shown whilst the rear face 12 is preferably rounded or bevelled at the side edges of the blade as indicated at 13 in Figures 3, 6 and 7. Furthermore, each blade 105 preferably decreases gradually in thickness from its narrow root portion 6 to its tip, as shown in Figure 8.

Referring now to the modification illustrated in Figure 9, the blades of the improved propeller may, if desired, be arranged alternately out of circumferential

- alignment or in different longitudinal or axial positions upon the hub 7. Figure 9 illustrates a six bladed propeller having its blades arranged in this manner and corresponding in frontal appearance with the propeller seen in Figures 2 and 4, that is to say, that although the alternate blades are arranged in different longitudinal positions on the propeller axis, the aforesaid characteristic feature relative to the width and sectoral shape of the blades as described with reference to Figures 1 and 2, also applies to the modified construction illustrated in Figure 9.
- 15 As the improved propeller rotates the water or fluid is forced through the passages or openings 10 and across the front and rear faces of the inclined blades to thereby effect propulsion, the formation and arrangement 20 of the blades as aforesaid, being such as to ensure a maximum forward thrust and a minimum of vibration and power losses.
- It will be understood that the characteristic features of this invention as defined by 25 the appended claims may be applied to a propeller having any desired multiplicity of sectoral blades which may be stamped or cut from a metal disc as indicated for instance in Figure 1 or may be formed by casting or otherwise as desired.
- Having now described my invention what I claim as new and desire to secure by Letters Patent is:—
- 30 1. A marine propeller comprising a hub; and a plurality of inclined blades on said hub, each of which constitutes a sector of a circle defined by the outer edges or tips of the blades, the combined frontal area of said blades being substantially equal to the complete circular area between said outer edges of the blades and the periphery of the propeller hub the blades being arranged in sets on said hub.
2. A marine propeller comprising a hub; and a plurality of inclined blades on said hub which constitute equal sectors of a circle defined by the outer edges or tips of the blades, the combined frontal area of said blades being substantially equal to the complete circular area between said outer edges of the blades and the periphery of the propeller hub, the side edges of said blades converging radially inwards from an arcuate outer edge to the propeller hub, so that, owing to the inclination of said blades to the propeller axis, relatively narrow inwardly converging openings or passages are formed between adjacent blades, the width of said openings being less than that of the blades and being determined solely by the inclination of said blades to the propeller axis, and the blades being arranged in sets on said hub.
3. A marine propeller comprising a hub; and a plurality of inclined blades each of which constitutes a sector of a circle defined by the outer edges or tips of the blades, the combined frontal area of said blades being substantially equal to the complete circular area between said outer edges of the blades and the periphery of the propeller hub, the alternate blades of said propeller being arranged in different longitudinal or axial positions upon the propeller hub to constitute sets of blades.
- In testimony whereof I affix my signature.

WILLIAM STELLNER.
